UNITED STATES PATENT OFFICE.

LEWIS W. EGGLESTON, OF BUFFALO, NEW YORK, ASSIGNOR TO AMERICAN RADIATOR COMPANY, OF CHICAGO, ILLINOIS, A CORPORATION OF NEW JERSEY.

AUTOMATIC DRAFT REGULATOR FOR BOILERS.

Application filed November 30, 1925. Serial No. 72,083.

My invention relates to improvements in heating apparatus, and the same has for its object more particularly to provide a simple, compact and efficient device for controlling 5 the rate of fuel consumption in a boiler, furnace or similar apparatus.

Further, said invention has for its object to provide a temperature regulating device which is controlled by means responsive to 10 conditions within the heating apparatus.

Further, said invention has for its object a temperature regulating device which is capable of adjustment to predetermine the temperature at which the heating apparatus is to 15 be maintained.

Further, said invention has for its object to provide an arrangement in which the position of the damper operating mechanism may be adjusted relative to the device responsive to 20 conditions within the boiler to predetermine the temperature at which said mechanism is to be actuated by said device.

Further, said invention has for its object to provide a draft regulator in which the adjustable means employed to predetermine the temperature at which the heating apparatus is to be maintained will also serve to manually control the admission of air to said apparatus.

Other objects and advantages will in part 30 be obvious and in part be pointed out hereinafter.

To the attainment of the aforesaid objects and ends my invention consists in the novel details of construction, and in the combination, connection and arrangement of parts 35 hereinafter more fully described and then pointed out in the claims.

In the accompanying drawings forming part of this specification—

40 Figure 1 is a side view, partly broken away and sectioned, showing a boiler provided with a regulator embodying the principles of my invention.

Fig. 2 is a central vertical side sectional view through the draft regulator.

Fig. 3 is a rear view of the regulator, and

Fig. 4 is an enlarged detail section on the line 4—4 of Fig. 2.

50 In said drawings there is shown a combined boiler and heater 10 comprising a hollow front section 11, a hollow back section 12, and a plurality of substantially loop-shaped in-

termediate sections 13. The front section 11 is provided with the usual fuel opening having a door 13^a, a slicing opening having a 55 door 14, an ash-pit opening having a door 15, and adjacent to its top with a flue opening provided with a door 16.

Within the boiler, between the front and back sections 11 and 12, are arranged a plurality of great bars 17 positioned side by side and longitudinally of the boiler. At the upper rear end the boiler is provided with a smoke outlet 18. In the back section 12, adjacent the bottom of the boiler, is provided 60 a cold air inlet 19 which communicates with the interior of the boiler below the grate 17.

Within the back section 12, near the upper end thereof, is formed a cavity 25 in which is positioned a thermostatic device comprising an outer casing 26 and an inner metallic bellows 27, the space between the casing 26 and bellows 27 being filled with an operating fluid, such, for example, as kerosene, alcohol, ether or any other suitable volatile or expandable fluid. The outer end of said bellows is joined to the casing 26 to seal the space between them. At its inner end the bellows abuts against the casing 26 and is provided with a head 29 having a tube 30 extending 70 outwardly therefrom for charging the device.

A tubular plunger 31 surrounding the tube 30 engages at its inner end the head 29 and extends outwardly and through a bracket 32 fixed to the rear of the boiler, said bracket 85 providing a bearing in which said tubular plunger works. The outer end of said plunger 31 is provided with a yieldable head 33 retained in position within the plunger 31 by means of the cap 34 threaded upon the outer end of the plunger, and through which said head 33 projects. A coil spring 35 is interposed between the head 33 and an abutment 36 disposed within the tubular plunger 31.

A lever 37 is pivotally suspended at its upper end, as more fully described hereinafter, and is provided with a bearing portion 38 engaging the head 33. At its lower end the lever 37 carries a damper plate 39 cooperating with the air inlet 19, and normally held 95 in open position by suitable biasing means, such as the spring 40.

As long as the plunger 31 is in its retracted position, the lever 37 will maintain

the air inlet open and permit of the increased supply of air which results in an increase of temperature. When the temperature rises sufficiently to contract the bellows, the member 33 and the upper end of the lever 37 move outwardly while the lower end of the lever moves inwardly to cause the plate 39 to seal the air inlet opening 19 until the rate of combustion is reduced. The long arm of the lever 37 greatly magnifies the movement of the damper plate 39.

In order to control the damper plate so that it will open and close at any desired predetermined temperature, there is provided, upon a spindle 41 fixed to the bracket 32, a rotatable member 42 having a spiral groove 43 therein. A handle 44 is secured to the outer end of the rotatable member for actuating the same. An annular member or collar 45 works upon the rotatable member, and is provided with a suitable projection such as the screw 46, operating in the groove 43 to cause said member 45 to travel along the shaft 42 upon the rotation thereof. The lever 37 below the bearing surface 38 thereof is pivoted at 47 between the lower arms 48 of a vertically disposed bifurcated member 49 which has upper arms 50 disposed at opposite sides of the collar 45 and pivoted at 51 there to. The member 49 intermediate its ends is also pivoted at 52 between the opposing portions of a horizontally extending member 53 pivoted at its inner end 54 to the bracket 32. The upper end of the spring 40 is attached to the outer end of said member 53, and the lower end to said lever 37 intermediate the ends of said lever 37. The damper operating mechanism is enclosed by a suitable casing 55 having an opening 56 therein through which the shaft 43 projects, and having openings 57 in the lower portion thereof for the admission of air, the portion 58 of said casing serving as a stop to limit the outward movement of the lower end of the lever 37. The upper portion of the casing 55 has formed thereon suitable indications or calibrations 59 for assisting the operator in adjusting to the desired temperature, the handle 44 in front of the casing being provided with a pointer 60 cooperating with said calibrations, and also constituting a stop engageable with a cooperating stop 61 to limit the rotation of the member 42 in each direction.

In operation, by rotating the member 42, the position of the bearing member or portion 38 of the lever 37 is varied relative to the head 33 of the responsive device. With the apparatus in the position illustrated the collar 45 is at its outermost limit of travel. When in this position the member 49 has moved the upper end of the lever 37 inwardly. This inward movement causes the bearing portion 38 to press against the head 33, whereby the lower end of the lever is swung about the pivot 47 into open position. Thus, by

this arrangement means is provided for manually controlling the admission of air through the inlet 19. As the handle is rotated counter-clockwise, looking at Fig. 3, the bearing portion 38 is moved outwardly relative to the plunger head 33, the spring 40 maintaining the lower end of the lever in open position. By thus adjusting the relative positions of the bearing portion 38 and the head 33, the temperature at which the responsive device operates to actuate the lever 37 is also controlled. As the member 42 is rotated counter-clockwise from the position illustrated proportionally higher temperatures must be attained before the lever is actuated by the head 33 to close the damper. When the temperature is correspondingly reduced the spring 40 will move the damper plate away from the inlet 19.

The member 53 provides a yieldable fulcrum to permit of the movement of the link or actuating member 49 without causing binding of the parts, and the connection of the spring 40 thereto is such that the relative position of the upper end of the lever 37 may be adjusted without appreciably varying the tension of said spring, the temperature at which the lever is actuated depending upon the position of the upper end of the lever, and not being controlled by variation of the tension of said spring.

The spring 35 serves to normally maintain the head 33 in its outer position, and permits of the yielding of said head when an unusual or undesirably large force is applied thereto which might otherwise rupture or damage the collapsible element or bellows.

The lever 37 is freely suspended, and is extremely sensitive to variations of the responsive device, and adjustment to predetermine the temperature at which the regulator operates is made by varying the relative positions of the head 33 and upper end 38 of the lever 37, the same adjusting means also serving to manually control the admission of air through said inlet 19.

While the above description contemplates control of the draft in accordance with the temperature developed within the boiler, it will be apparent that said control may be made dependent upon the pressure in the boiler by merely removing the casing 26 and exposing the bellows 27 directly to said pressure.

It is to be noted that all the openings in the front of the heating apparatus are closed by doors which are preferably ground to fit tightly against or over said openings in order to prevent any admission of air to the interior of the apparatus, and that the primary air necessary to support combustion is admitted to the heating apparatus wholly through the air inlet 19, which is automatically controlled.

The above description illustrates the prin-

ciples embodied in my invention, but it will be understood that various changes and modifications may be made within the scope of the invention as defined by the annexed 5 claims.

Having this described my said invention, what I claim and desire to secure by Letters Patent is:

1. The combination of a boiler having a 10 main air supply inlet, with a support, a member movably mounted on said support, a lever pivotally suspended at its upper end from said member, a closure for said inlet connected to the free end of said lever, means 15 responsive to conditions within the boiler and associated with said lever at the pivoted end thereof for actuating said closure to control the passage of air through said inlet; said lever tending to maintain said closure in 20 open position, and means connected to said movable member for reciprocating the same to vary the position of said lever relative to said responsive means for controlling the 25 operation of said lever, substantially as specified.

2. The combination of a boiler having a main air supply inlet, with a support, a member movably mounted on said support, a lever pivotally suspended at its upper end from 30 said member, a closure for said inlet connected to the free end of said lever, means responsive to conditions within the boiler and having a plunger engaging said lever above the pivot thereof; said responsive means serving 35 to actuate said lever to control said closure, and means connected to said movable member for adjusting the same towards and away from said plunger to permit of the manual control of said closure; said last- 40 named means serving to control the temperature at which said closure is actuated by said responsive means, substantially as specified.

3. The combination of a boiler having a 45 main air supply inlet, with a closure for said inlet, a lever to which said closure is attached at one end, means responsive to conditions within the boiler and associated with the other end of said lever for actuating the same, 50 a support, a rotatable actuating screw thereon, and a pivoted member traveling on said screw and connected to said lever for varying the position of said lever relative to said responsive means whereby to control the tem- 55 perature at which said closure is actuated by said responsive means, substantially as specified.

4. The combination of a boiler having a main air supply inlet, with a reciprocating 60 member, a pivoted supporting arm connected to said reciprocating member, a lever pivotally suspended at its upper end from said arm, a closure for said inlet connected to the free end of said lever, means responsive to 65 conditions within the boiler and associated

with the upper end of said lever for actuating the same, and means for actuating said reciprocating member whereby to adjust the position of said lever relative to said responsive means, and control the temperature at which 70 said closure is actuated by said responsive means, substantially as specified.

5. The combination of a boiler having a main air supply inlet, with a support, a rotatable actuating member thereon, a member 75 adapted to travel on said actuating member when the same is rotated, a horizontally extending member pivoted at its inner end and disposed below said actuating member, a vertically arranged arm pivoted intermediate 80 its ends to said horizontally extending member and at its upper end to said traveling member, a lever pivotally suspended at its upper end from the lower end of said arm, a closure connected to the lower end of said 85 lever, and means responsive to conditions within the boiler and having a plunger engaging said lever above the pivot thereof, substantially as specified.

6. The combination of a boiler having a 90 main air supply inlet, with means responsive to conditions within the boiler and having a plunger projecting therefrom, a support 95 above the same, a rotatable screw upon said support, a collar adapted to travel upon said rotatable screw, a pivoted member disposed between said rotatable screw and said responsive means, a vertically extending arm pivoted intermediate its ends to said pivoted member and at its upper end to said collar, 100 a lever pivotally suspended at its upper end from said arm and having a portion above its pivot engaging said plunger, a closure for said inlet connected to said lever at its lower end and controlled by the operation of said responsive means, and a spring connected at one end to said pivoted member and at its opposite end to said lever; said rotatable screw serving to adjust the position of the pivot of said lever relative to said plunger 110 to permit of the manual control of said closure and to control the temperature at which said closure is actuated by said responsive means, substantially as specified.

7. The combination of a boiler having a main air supply inlet, with a reciprocating member, a supporting arm pivoted intermediate 115 its ends and at its upper end to said reciprocating member, a lever pivotally suspended at its upper end from the lower end of said arm, a closure for said inlet connected to the free end of said lever, means responsive to conditions within the boiler and associated with said lever for actuating the same, and means for actuating said reciprocating member, substantially as specified.

8. The combination of a boiler having a main air supply inlet and a support, with a rotatable actuating member thereon, a member adapted to travel on said actuating mem- 130

ber when the same is rotated, a vertically arranged arm pivoted intermediate its ends and at its upper end to said traveling member, a lever pivotally suspended at its upper end from the lower end of said arm, a closure connected to the lower end of said lever, and means responsive to conditions within the

boiler and associated with said lever for actuating the same, substantially as specified.

Signed at the city of New York, in the 10 county and State of New York, this 28 day of November, one thousand nine hundred and twenty-five.

LEWIS W. EGGLESTON.
